DISPLAY PACKAGE OF CHRISTMAS TREE ORNAMENTS

David W. Fisherman, New York, N. Y., assignor to New York Merchandise Co., Inc., New York, N. Y., a corporation of New York

Application July 6, 1956, Serial No. 42,158

Term of patent 7 years

(Cl. D58—12.6)

Fig. 1

I claim:

The ornamental design for a display package of Christmas tree ornaments, as shown.
